(57) **CLAIM**

The ornamental design for a shoe, as shown and described herein.

DESCRIPTION

FIG. 1 is a perspective view of a shoe showing our new design.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

FIGS. 1-7 depict views of a right shoe showing our new design. Respective views of a left shoe showing our new design are mirror images of FIGS. 1-7.

1 Claim, 7 Drawing Sheets
